UNITED STATES PATENT OFFICE.

HUGH L. ROBERTS, OF ROANOKE, VIRGINIA.

DRIFTING VALVE.

Application filed July 5, 1921. Serial No. 482,591.

This invention relates to improvements in drifting valves for locomotives, the general object of the invention being to improve and simplify the construction and operation of 5 the valve forming the subject matter of the patent granted to me on May 29, 1923, numbered 1,457,272.

Another object of the invention is to provide an auxiliary steam supply for moving 10 the valve into drifting position as soon as the throttle is closed with means for renewing this supply when the throttle is open.

This invention also consists in certain other features of construction and in the 15 combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:—

25 Figure 1 is a diagrammatic view showing the application of my invention.

Figure 2 is a sectional view through the valve chest which controls the flow of steam to and from the auxiliary supply tank.

30 Figure 3 is a sectional view through the drift valve and showing means for supplying the tank with steam from the cylinder.

Figure 4 is a view similar to Figure 3 showing the parts in drifting position.

35 Figure 5 is an enlarged sectional view through the valve 26.

In these views 1 indicates the steam dome of the locomotive boiler, and 2 the lubricator which is connected with the dome by the 40 pipes 3, in one of which is located the valve 4.

The drifting valve is shown at 5, the pump at 6, and 7 indicates the throttle lever. The drift valve consists of the casing 8 and the pistons 9, 10, 11 and 12 which are connected together by the rods 13. Piston 12 is larger than the other pistons and works in an enlargement 8' of the casing. The other pistons are of the same diameters but piston 9 is double headed to provide the groove 9'.

45 A pipe 14 connects the end of the chamber formed by the enlargement 8' with a steam

chest of one of the cylinders or with the pipe leading to the steam chest so that when the throttle is open steam will flow into the chamber to hold the pistons in inoperative position, as shown in Figure 3. A piping 15

connects the casing, adjacent piston 11, with the exhaust pump 6 and piping 15' leads the exhaust from the stoker to said piping 15 so that the oil laden steam from the pump and

55

stoker will flow into the casing and will exhaust through the outlet 16 when the drifting

60

valve is in a position normally held when the throttle is open, said position being hereinafter referred to as normal position

65

as against the position taken when the throttle is closed and the pistons moving, which is termed drifting position. A by-pass 17 connects the piping 15 with the exhaust so

70

as to prevent the exhaust of the pump and stoker being entirely closed if the piston 11 should fail to pass over the port leading to

75

pipe 15. The inlet end of this pipe 17 is so formed that the exhaust will flow through the casing, unless prevented, as this path

80

will offer the least resistance. Piping 18 connects the casing with the coupling 19 which connects the pipes 3 together so that when steam is turned on to the lubricator

85

some of the steam will pass to the drifting valve. Piping 20 connects the casing with the steam chest of the cylinders, the connection of this piping with the casing 8 being a

90

forked one, as shown at 20'. A pipe 21 connects the piping 15 with a point in the casing 8 which is in alignment with the

95

groove 9' of piston 9 when the valve parts are in normal position. A pipe 22 connects the space formed by the groove 9' with the

100

exhaust 16 and a port 9'' connects the space formed by the groove 9' with the space between the pistons 9 and 10 so that the

steam flowing into the casing from pipe 18 can flow to exhaust through the port and pipe 22 when the valve parts are in inoper-

95

ative position. This will prevent steam from being trapped in the space between the pistons 9 and 10, when the parts are in inoperative position, which might interfere with the operation of the device by permitting the steam to condense in the device.

100

Pipe 21 serves to introduce some of the oil

laden steam from the pump and stoker into the casing to lubricate the heads of piston 9. A tank 23 is connected with the small end of casing 8 so that the steam in this tank 5 will act to force the pistons into drifting position as soon as the throttle is closed. Figure 3 shows this tank as being connected directly with the casing by means of pipe 24 and to the cylinder of the engine by means 10 of pipe 25, said pipe 25 having a check valve 26 therein for preventing the steam from returning to the cylinder when the throttle is closed. Figures 1 and 2 show the tank 23 as being connected with a valve chest 27, 15 this chest being connected with the steam supply of the lubricator by piping 28 and with the small end of casing 8 by the piping 29. This valve chest is formed with a pair 20 of chambers 30 and 31 which are each provided with a valve seat 32 for receiving the valves 34 and 35. These valves are held to the seat by the springs 36. The lower part of chamber 30 is connected with the upper part of chamber 31 by means of the passage 25 37 so that when valve 34 is open the steam from the boiler flowing through pipe 28 will pass into the valve chest into chamber 30, through port 37 into chamber 31 and through pipe 38 into the tank 23. As valve 35 is 30 closed no steam can pass into pipe 29 which leads to the drifting valve. When valve 35 is opened and valve 34 closed, this steam will flow from the tank 23 past the valve 35 into pipe 29 and thus act upon the valve parts to 35 move the same into drifting position. The valves 34 and 35 are controlled from the throttle lever 7 by means of the link 39 which is connected with the stem of the T lever 40 which is pivoted to a part of the valve chest 40 27. The arms 41 of this lever are arranged to engage the stems of valves 34 and 35 so as to open the valve 34 when the throttle lever is moved to open the throttle and to open valve 35 when the throttle lever is moved to 45 closed position.

From the above it will be apparent that when the throttle is closed the accumulated steam in tank 23 acting against piston 9 will move the parts into drifting position with 50 the exhaust from the pump and the stoker passing into the space between the pistons 10 and 11 so that this oil laden steam will pass into the cylinders of the engine to lubricate the same. The steam flowing through pipe 55 18 will also pass into the cylinders as piston 10 will straddle the fork 20 when the parts are in drifting position. This steam mixing with the oil laden steam will prevent explosions of the oil in the hot cylinders. The 60 passage of this steam through the right hand part of the fork will create a suction in the left hand part so as to suck the oil laden steam into the cylinders so that the pump and stoker do not have to work against back 65 pressure. As soon as the throttle is opened

some of the steam flowing to the cylinders will pass through pipe 14 into the large end of the casing 8 and this steam acting against the large piston 12 will return the parts to inoperative position. If an excess pressure 70 should occur in the cylinder when the throttle is closed this pressure will act against the piston 12 and move the parts to inoperative position and thus cut off the supply of oil and steam to the cylinders and permit 75 the exhaust from the pump and stoker to pass to exhaust. The valve will not go to drifting position again until the throttle has been opened, the tank recharged and the 80 throttle closed again. The pressure in the tank then will move the valve to drifting position.

By my invention the engine cylinders and the parts of the drift valve are oiled by the oil in the exhaust from the pump and stoker. 85 The valve is absolutely automatic and requires but very little attention. It also acts to save fuel as it requires but little boiler steam on account of using the air pump and stoker exhaust.

In the construction shown in Figures 1 and 2 the tank 23 is connected with the steam supply when the throttle is open so that said tank is stored with steam and then when the throttle is closed the tank is connected with the drifting valve so that the steam therein 95 will move the parts to drifting position.

It will be seen that when the pistons are in drifting position the tank 23 will exhaust through the pipe 22 so that the steam from this tank will not interfere with the return of the parts to inactive position when the throttle is again opened.

It is thought from the foregoing description that the advantages and novel features 105 of my invention will be readily apparent.

I desire it to be understood that I may make changes in the construction and in the combination and arrangement of the several parts, provided that such changes fall within 110 the scope of the appended claim.

What I claim is:—

In a locomotive, a drifting valve comprising a casing, an enlarged end on said casing, a plurality of pistons movable in said casing, one of the pistons being of larger diameter than the others and movable in said enlarged end, an inlet at one side of the casing at a point adjacent the enlarged end, an outlet pipe opposite the inlet, and both outlet and inlet being arranged at one side of one of the pistons when in normal position, a by-pass connecting the inlet and outlet, one of said pistons having an annular groove, a steam supply pipe having connection with the casing, at a point in alignment with the groove when the piston is in normal position, a second pipe leading from the casing in communication with the groove 115 serving as an outlet, an additional pipe 120

communicating with the cylinder between certain of said pistons and having connection with the steam chest of the cylinders of the engines, a pipe leading from the casing to the lubricator, so that some of the oil-laden steam will pass into the valve, a tank, a pipe connecting the casing and the tank, and a pipe controlled by the throttle connected to the enlarged end of the casing so that steam admitted through this pipe will 10 return the valve to normal position.

In testimony whereof I affix my signature.

HUGH L. ROBERTS.
